UNITED STATES PATENT OFFICE.

JOHN SCHMERSAHL, OF NEW YORK, N. Y.

COMBINATION CRADLE AND CHAIR.

No. 825,984.

Specification of Letters Patent.

Patented July 17, 1906.

Application filed August 30, 1904. Serial No. 222,741.

To all whom it may concern:

Be it known that I, JOHN SCHMERSAHL, a citizen of the United States, residing at New York, in the borough of Manhattan and State of New York, have invented a new and useful Combination Cradle and Chair, of which the following is a specification.

This invention relates generally to chairs, and more particularly to a combination high chair and a cradle or swing, the object being to provide a simple and efficient device for the use of children; and the invention consists in the novel features of construction, combination, and arrangement, all of which will be fully described hereinafter, and pointed out in the claims.

In the drawings forming a part of this specification, Figure 1 is a perspective view of a combination-chair constructed in accordance with my invention, the device being arranged as a chair and having the tray in place. Fig. 2 is a side elevation of the device arranged as a cradle or swing. Figs. 3 and 4 show details of construction.

In the practical embodiment of my invention I employ the legs A, connected by brace-rounds A', and at their upper ends the legs are connected by means of the side pieces B, having suitable bearings C, through which pass the pivot-bolts D, from which suspend the hangers E, connected at their lower ends to the seat F, said seat having a back G pivotally connected to the rear end thereof, the side members of the back projecting below the seat, as shown at G', and it will be noted that the side edges of the seat are cut away at the rear ends, as shown at F', in order to permit the side members of the back to be swung back and forth.

The forward end of the seat is provided with depending legs H, carrying a footboard I, and toggle-levers K and L are pivotally connected to the legs H and seat F and also to the rods M, extending from the lower ends of the side members of the back to the pivotal connection between the toggle-levers, said construction being designed and arranged so that when the back of the chair is thrown back, as indicated in Fig. 2, the foot-rest will be thrown up, so that the legs of the child will be properly supported while the body is in a recumbent position, and for the

purpose of holding the back of the chair in either an upright or inclined position I employ a ratchet-bar N, pivoted at N' to the back of the chair-back and having a spring O, which normally tends to throw the lower end forwardly, said lower end working through a slotted catch-bar P and against which the ratchet-bar is adapted to engage for the purpose of locking the seat and back at any desired point of adjustment.

T indicates a tray pivotally connected at one end to one of the side pieces B by means of a headed pin T', which engages a slotted casting T², arranged upon one side of the side piece B. The opposite end of the tray is provided with a catch T³, which is adapted to engage a pin T⁴, carried by the other side piece B, and when the tray is locked across the forward ends of the side pieces all motion of the chair is arrested, inasmuch as the arms W of the seat F will engage the under side of the tray T, as most clearly shown in Fig. 4.

When it is desired to use the chair as a swing or cradle, the tray is unfastened and swung over upon its pivot, and the chair is then free to swing, and by adjusting the back and foot rest portions the device can be transformed into a swing or swinging cradle, if desired.

Having thus fully described my invention, what I claim as new, and desire to secure by Letters Patent, is—

1. The combination with a support of the hangers pivoted thereto, the chair-seat connected to the hangers, the back, pivoted to the seat, the foot-rest pivoted to the seat, the spring-actuated ratchet-bar attached to the back, and the slotted bar attached to the seat, and through which the ratchet-bar passes, the toggle-levers connecting the seat and foot-rest, and the rods connecting the toggle-levers to the lower end of the back, as set forth.

2. The combination with a support provided with bearings at its upper end carrying pivot-bolts, of hangers loosely mounted on said bolt, carrying a chair-seat, a back pivoted to the seat, and provided with downwardly-projecting side members, rods loosely connected to the end of the side members, depending legs pivotally connected to the forward end of the seat, carrying a foot-

board, links pivoted to the seat and legs adjacent their connecting-points, and connected to the free end of said rod, a tray loosely connected to the support at one side provided with a catch adapted to engage a pin secured to the other side, a slotted bar projecting outwardly from said seat and a

spring-actuated ratchet-bar carried by the back adapted to extend through the slot in the bar, for the purpose described.

JOHN SCHMERSAHL.
